UNITED STATES PATENT OFFICE.

JOHN NEUMAIER, OF MILWAUKEE, WISCONSIN, ASSIGNOR OF THREE-FOURTHS TO GEORGE L. BALDAUF, OF MILWAUKEE, WISCONSIN.

AUTOMATIC RAILWAY-SIGNAL.

No. 817,131.

Specification of Letters Patent.

Patented April 3, 1906.

Application filed July 8, 1905. Serial No. 268,791.

To all whom it may concern:

Be it known that I, JOHN NEUMAIER a citizen of the United States, residing at Milwaukee, county of Milwaukee, and State of Wisconsin, have invented new and useful Improvements in Automatic Railway-Signals, of which the following is a specification.

My invention relates to improvements in automatic railway-signals.

10 The object of my invention is to provide a device by which a signal may be automatically communicated from a train approaching a given station to the second or next succeeding station, also whereby as the train passes the first station it will automatically turn down the signal at such station which has previously been set by such train, and the operators at each succeeding station throughout the entire line of railway will be notified 15 in advance of the train which is approaching regardless of the direction it is moving, and whereby all the signals along the line after serving their purpose are reset and left in their normal position preparatory to being 20 acted upon by the next succeeding train, and also whereby a signal may be given in the locomotive as it passes the several stations along the railway.

My invention is further explained by reference to the accompanying drawings, in which—

Figure 1 represents a diagrammatic view of the system including two stations and four contact-bearings for actuating the electric 35 circuits along the railway system. Fig. 2 represents a side view, part in section, of the primary-switch mechanism which is actuated by the wheels of a moving train as it passes along the railway-track. Fig. 3 is a trans- 40 verse section drawn on line $x-x$ of Fig. 2. Fig. 4 represents a side view, and Fig. 8 a top view, of the signal which is located in the several stations and also in the locomotive. Fig. 5 represents a rear view of the cab of a 45 locomotive provided with a signal. Fig. 6 represents my device used in connection with the railway-switch, whereby a signal is communicated from a given switch, when closed for an approaching train on one line, to trains 50 approaching such switch from branch lines leading to the same from either direction; and Fig. 7 represents a diagrammatic view including the main line, branches, and switches leading to the same.

In describing my system the several co- 55 operating parts are referred to by the same reference characters in the order of their action after the primary switch has been actuated by contact of the wheels of the passing train.

Referring to Figs. 2 and 3, 1 represents one 60 of the rails of an ordinary railway-track.

2 is a contact-lever the upper end of which is located in close proximity to the flange of the rail, whereby the wheels of a passing 65 train will be brought in contact therewith as the train is passing. The lever 2 is pivotally supported from a case 3 upon the transversely-arranged shaft 4. The case 3 is preferably located below the level of the track 70 and provided with a water-tight cover 5, and the internal operative mechanism is shielded from contact therewith by the insulation 6.

The device thus far described is located 75 upon the respective sides of the several stations along the railway system, whereby as a train approaches the station from either direction the lever 2 will be inclined, as stated, in the direction of the moving train.

Assuming that a train is approaching the 80 station from the right, the upper end of the lever 2 will be inclined toward the left, or in the direction indicated by the arrow, whereby motion will be communicated from the lower end of said lever through the support- 85 ing-shaft 4 and bifurcated lever 7 to the switch-bar 8, whereby the switch-bar 8 is brought in contact with the terminals 9 and 10 and whereby an electric circuit will be es- 90 tablished between the battery 11 of such station and signal 12 of the next station through the conductor 13, terminals 9 and 10, and conductors 14' and 32, the return-circuit from said signal being formed through the conductor 33 and rail 1, conductor 2', earth- 95 circuit 3', and conductor 16 and battery 11, whereby the bell 4' of said signal 12 at the second or next succeeding station, which we will call "B," is operated and whereby the station-master at the station B is notified of the 100 train approaching station A and also whereby the agent at the station B will understand that he is to hold any train which may be approaching station B from the opposite direction.

105 It will be understood that when the train is in the act of passing the station A toward the station B, the wheels of the cars are

brought in contact with the contact-lever 2, located at the side of said station, whereby a circuit is closed between the switch connected with the lever 2 back to the station preceding A and whereby the operator at the station preceding A will be notified that the track is clear between such station and the station A.

The electric circuit is closed between the contact-lever 2 at station B to reset or clear the signal at signal-station A, Fig. 1, through the switch-arms 18, terminal 19, conductor 20, electromagnet 21, conductor 22, battery 11, conductor 16, the earth and railway-rail 1, and the conductor 23 to the switch-arm 18. When the circuit is thus closed and the electromagnet 21 is energized, the switch-bar 8 will be thrown toward the left in contact with said electromagnet 21 and out of contact with the terminals 9 and 10.

It will be understood that the device shown in Figs. 2 and 3 represents the devices located at each of the several stations and that the several parts of said devices are referred to by the same reference characters. It will also be understood that when the switch-bar 8 is thrown in contact with the terminals 9 and 10 the electromagnet 24 will be energized, whereby the armature 25 of said signal 30 is drawn into contact therewith and the pawl 60 is drawn out of contact with the teeth of the ratchet-wheel 61, whereby the signal-actuating weight 62 is released and permitted to descend of its own gravity, when motion is 35 communicated from said descending weight to the signal 27 through the cord 63, cord-supporting drum 64, drum-supporting shaft 65, disk 66, radial arms 67, reciprocating bar 68, and the two-armed lever 69, whereby said 40 signal 27 is thrown to the vertical. The bar 68 is slidably supported by the standards 70 70 and is connected with the short arm of the lever 69 by the pin 71, which is rigidly affixed at one end in the bar 68 and operates in 45 the slot 72, formed in the short arm of said lever 69. When the bar 68 has been thus thrown toward the right by the action of the descending weight, it is locked in such position by the armature 73, which serves as a 50 catch, and the same is yieldingly retained in contact with the side of the bar 68 by the spring 74, whereby the end 75 of the bar 68 is brought in front of said armature, and said armature engages the end of said bar and retains the signal 27 in the vertical position. 55 When, however, the moving train has reached the next succeeding station and the signal is no longer required, the armature 73 is withdrawn from the end of the bar 68, 60 when the bar 68 is released and the signal 27 is free to drop of its own gravity to the position shown in Fig. 4. The armature 73 is thus withdrawn from the bar 68 by the action of the electromagnet 76 in station A, 65 when the circuit is closed at station B.

It will be understood that the drum 64 is turned, the cord 63 wound thereon, and the weight 62 raised thereby by the manual act of a person preparatory to being actuated automatically by the gravity of the weight 62. 70 The gravity of the weight 62 is such that it can be utilized when released for not only actuating the signal 27 and also for closing the circuit with the signal-bell and causing it to be rung, but the power of said descending 75 weight may also be used for opening steam and air controlling valves through which steam or air under pressure may be led to the cylinders and pistons of the ordinary brake mechanism, whereby the brakes of a train 80 may be automatically set and a train stopped by closing the electric circuit which communicates with the electric terminals with which the passing train is brought in contact.

80 represents a valve for controlling the steam or compressed air by which the brake mechanism may be operated. The valve 80 is connected with the reciprocating bar 68 through the arm 81, pivotal connection 82, link 83, pivotal connection 84, and valve-actuating lever 85. Thus it will be understood that when the weight 62 is released by withdrawing the armature 25 from the teeth of the ratchet 61 said reciprocating bar 68 will be thrown toward the right, carrying 95 with it the link 83 and the valve-actuating lever 85, whereby the valve 80 is opened and the brake-actuating medium and the brake may be automatically set. When the signal 27 is brought to the vertical, as previously 100 described, the electric circuit is closed between the battery 28 and the signal-bell 4' through the terminals 29 and 30, whereby said bell is operated in the ordinary manner.

It will be understood that the signal 27 105 will be retained in the vertical position until the electromagnet 76 is energized and that the electromagnet 76, located in the cab of the locomotive, will be energized as soon as the switch-bar 8, located at the side of the 110 track is brought in contact with the terminals 9 and 10 and that the bell will ring an instant only as the ends of the terminal 29 pass across the terminal 30, when it will cease to ring until the contact-bearing of the terminal 115 29 is caused to again pass the terminal 30 on the return movement of the signal 27.

Assuming that the contact-bearing 32' is in contact with the rail 31, as shown in Fig. 5, the electric circuit is formed on one side through the conductor 48, which communicates with the battery 41 (shown in Fig. 7) through the conductor 47 and switch 39, and on the other side from the rail 31 through the contact-bearing 32', conductor 33', and thence to the signal 34 in the cab, thence from the signal back through the conductor 35, car-axle 36, car-wheel 37, rail 1, and thence through the ground-circuit 3' back to the battery 41, thus completing the circuit. 130

When the electromagnet 76 is energized, as stated, by the closing of the electric circuit, the armature 73 is drawn from the end 75 of the bar, thereby releasing the reciprocating bar 68, when the signal 27 is free to drop, as stated, from the vertical position to that shown in Fig. 4, whereby said bar 68 is thrown to the left against one of the radial arms 67 preparatory to being again actuated 5 when the armature 25 is withdrawn from one of the teeth of the ratchet 61. It will be understood that the weight of the signal 27 is such as to move said bar 68 and actuate the valve 80 through the connecting parts. It 10 will also be understood that as the weight 62 descends it is brought in contact with the terminals 62' and 63', thereby closing the circuit between the battery 28 and the bell 4', whereby the signal is sounded and the station-agent notified that the weight 62 has run 15 down and needs rewinding preparatory to being again acted upon. It will also be understood that the track at each station along a railway-line is equipped in like manner with 20 two signal-operating devices, one located upon each side of each station, both of which are connected with another signal in the station, whereby the approach of a train from either direction is indicated through such 25 signals also that when a train passes through any one of the stations along the railway-line it will successively act upon both of said signal-operating devices in the manner described, whereby a signal will be operated not 30 only in the next succeeding station to indicate the approaching train, but a signal will also be operated in the preceding station to indicate that the train has passed the intermediate station and that the way is clear for 35 the following train from the preceding station. The same is true when trains are passing in the opposite direction.

To provide for operating the signal in the locomotive while the train is approaching 40 station A from the right, the signal at station B being set, a separate contact-rail 31 is located parallel with the rails of the track and insulated from the ground, which rails 31 are connected with one of the electric batteries 11 45 on the left-hand side in station B and the signal 34, located in the locomotive, through the following conductors, beginning with the battery 11, conductor 13, terminals 9 and 10, switch-bar 8, conductor 14', conductor 32'', rail 31, conductor 32', conductor 33', thence 50 through the signal 34 and back to the battery 11 through the conductors 35, axle 36, wheel 37, and rail 1, conductor 2', and thence through the ground-circuit 3' and conductor 55 16, whereby the signal-bell in the locomotive will be caused to ring while the locomotive is thus passing the station. If, however, the station B is clear, the signal in the locomotive at station A will not be sounded, as the circuit with the bell in the locomotive will be 60

broken by the bar 8 being thrown out of contact with the terminals 9 and 10 at station B. It will also be understood that when the train is thus approaching station A from the right and the bell in the locomotive is being sounded in the manner described the signal at the station B will be simultaneously sounded. Assuming that the train has now passed the station B, it is brought in contact with the contact-lever 2 at the left of station B, where- 70 by the signal-bell in station A is sounded, indicating that the way is clear, the electric circuit being formed between said contact-lever 2 and said signal-bell in the station, while at the same time an electric circuit, 75 is formed from the signal 12, as follows: through the conductor 13, rail 1, and from thence to the arm 18, thus closing the circuit, whereby the signal will be sounded at A, indicating that the train has passed the station B 80 and the way is clear. Referring to Fig. 7, 85 31 31 indicate the contact-rails, located upon the respective sides of switches 38 38 of a main track C. 31' 31' indicate the contact-rails upon the respective sides of the switches 90 39 39 of the other main track.

It will now be understood that when a train is approaching a switch and the contact-brush 32', a similar brush being preferably located on each side of the engine, is brought 95 in contact with the rail 31 if the switches leading from the approaches on such track or any other track are closed the electric circuits communicating through such switches will be closed and the signal in the locomotive will be sounded, that the engineer in such locomotive will be notified that such switches are closed and that there is danger of collision from approaching trains. For example, assuming that the switches 38 and 100 39 upon the left of Fig. 7 are closed and the locomotive is in electrical connection with the contact-rail 31 upon the right in said figure, the electric circuits showing such switches to be closed will be formed through 105 the following conductors, to wit: from the track 31, brush 32', conductor 33', signal 34, conductor 35, axle 36, wheel 37, rail 1, conductor 2', ground-circuit 3', conductor 40, battery 41, conductor 42, switch 43, terminals 44 and 45, conductors 46 and 47, conductor 48, the latter leading to the rail 31. 110

It will of course be understood that when the switches are reversed the electric circuit communicating through said switches will be 115 opened and the signal will fail to be sounded in the locomotive, when the engineer will understand that the switches are open and that the way is clear for the passing train. It will also be understood that when a train is approaching any of the switches in the system from either direction and the switches are closed the system will be operated in the manner described or will fail to operate in case said switches are open, whereby the en- 120 125 130

4
gineer on any train approaching any of the switches will be informed as to whether the switches are open or closed.

49 represents a switch with which the track 5 1 is adapted to be connected, motion being communicated to the switches from the approaching lever 50 to said rails through the links 51 and connecting-bars 52 in the ordinary manner.

10 It will be understood that the contact-bars 31 and 31' are preferably located at considerable distances from the switches, so that when a signal is sounded showing that the switches communicating with an approaching 15 train are closed the engineer will have time to stop his train before reaching such switch, and thus avoid a collision, which might otherwise occur. The contact-lever 2 is yieldingly retained in the vertical when not 20 actuated by the wheels of a passing train by and between the spiral springs 2', one end of each of said springs being rigidly connected with the spring-inclosing walls 3'', and the opposite ends of said springs are connected 25 with said lever 2. It will also be understood that the switch-bar 8 is thrown toward the right in contact with the terminals 9 and 10 by contact of the lever 7 with the pin 7', while said bar 8 is thrown toward the left by 30 contact of said lever 7 with the other pin 8', which projects laterally from the side of said switch-bar, and by the electromagnet 21. The switch-arm 18 is brought in contact with the terminal 19 by contact of the moving 35 train with the lever 2 from left to right. The distance between the pins 7' and 8' is such as to permit said switch-bar 8 to move toward the left far enough to contact with the electromagnet 21 or toward the right far enough 40 to contact with the terminals 9 and 10 without moving lever 7. It will be understood that the lever 7 serves to throw said switch-bar in contact with either the electromagnet 21 or the terminals 9 and 10 as the arm 2 is 45 moved toward the right or left by the passing train and that said switch-bar 8 will then remain at the extremity of its movement in either direction, while the lever 7 is brought to the vertical by the action of the spiral 50 springs 2' 2'. Thus it will be understood that when the electromagnet 21 is energized the switch-bar 8 will be moved to the left without moving the lever 7 and will remain in contact with the electromagnet until 55 moved away by the lever 7, also that when the switch-bar is thrown toward the right by the action of the lever 7 it will remain in contact with said terminals 9 and 10 until the moving train has been brought in contact 60 with the arm 2 and the arm 2 thrown toward the right.

To prevent the waste of electric energy from the battery when the wheels of a train are left in contact with the lever 2, I have 65 provided a means for automatically breaking

the electric circuit after the signal 27 has been acted upon, as hereinafter explained. When the signal 27 is in the position shown in Fig. 4, the electric circuit is completed with the signal through the conductor 32, terminal 90, two-armed lever 69, terminal 91, conductor 92, electromagnet 24, conductor 93, conductor 33, thence through the rail 1 to the ground, whereby the electromagnet 24 is energized and the armature 25 is released and the signal 27 thereby thrown to the vertical, as previously described, whereby the electric circuit communicating with the battery is broken.

When the signal-supporting lever 69 has 80 reached the vertical, it is out of circuit with the battery so long as the train stands at rest, notwithstanding the wheels of the train are in contact with the lever. When, however, the train has moved out so that the 85 wheels are brought out of contact with said actuating-lever 2 and passes on to the next succeeding station and the lever 2 at such station is inclined in the opposite direction, the electric circuit will be closed with the 90 battery through the terminals 95 and 96 and the signal-supporting lever 69, whereby the electromagnet 76, which is connected with the terminal 96, is energized and the armature 73 withdrawn from the reciprocating 95 lever 68, whereby the signal 27 is released and permitted to fall again of its own gravity to the position shown, whereby it is obvious that when the wheels of a passing train are brought in contact with the lever 2, as stated, the circuit will be closed with the battery for 100 an instant only while the signal 27 is being thrown to or from the vertical and the battery thereby prevented from becoming de-energized. When the lever 69 is brought in 105 contact with the terminals 95 and 96, the electric circuit is closed between the electromagnet 76 with the battery through the conductor 20, conductor 13', terminals 95 and 96, lever 69, conductor 97, electromagnet 76, 110 and conductor 98, conductor 33, rail 1, and from thence completed through the ground, whereby as said electromagnet 76 is energized and the armature connected therewith is withdrawn from the reciprocating bar 68 115 the bar 68 will be thrown toward the left by the gravity of the signal 27 as it drops back to the position shown.

Having thus described my invention, what I claim as new, and desire to secure by Letters Patent, is—

1. In an automatic electric signal system for railways, the combination with each of the several stations along the railway, of two electric switches, one located upon the respective sides of each station in close proximity to the track of the railway, each provided with a contact-bar being adapted to be actuated by the wheels of a passing train; means connected with one of the switches 130

upon one side of any given station for closing an electric circuit through said switch; a battery and a signal located in the next succeeding station along the line, whereby a signal 5 will be given in such station, of an approaching train; and means connected with the electric switch upon the other side of such first-named station for closing an electric circuit through said switch; a battery and a 10 signal located in the preceding station, whereby as a train passes the two switches of any given station, a signal will be communicated both to the next succeeding station ahead of such approaching train and back to 15 the preceding station, giving notice that the track is clear, from such preceding station.

2. In an automatic electric signal system for railways, an electric switch mechanism comprising a water-tight receptacle located 20 below the track, provided with an insulating-lining; an electromagnet located within and insulated from said receptacle; an electric switch-bar, one end of which is normally retained in close proximity to said electromagnet; electric terminals located in close proximity to the opposite end of said switch-bar; a contact-arm pivotally supported at one end from said receptacle in close proximity to the 25 track of a railway; an arm-supporting shaft revolvably supported from the walls of said receptacle, one end of said shaft being extended through the walls of said receptacle and connected with said contact-arm; means for yieldingly retaining said contact-arm in a 30 vertical position preparatory to being inclined in either direction by contact of the wheels of a passing train; a switch-actuating arm suspended from the inner end of said shaft in connection with said switch-bar; 35 electric conductors communicating with the terminals at one end of said switch-bar for closing an electric circuit with a signal at a station upon one side of said switch mechanism and electric conductors connected with 40 the switch-actuating arm for closing an electric circuit with a station upon the other side of said switch mechanism, substantially as set forth.

3. In an automatic electric signal system 50 of the class described, the combination with a railway-track, of an electric switch adapted to receive its initial action from the wheels of

a passing train; electric signals located in the railway-stations upon the respective sides of said switch mechanism; electric conductors 55 communicating between said switch mechanism and said signals; electric signals located in the locomotives upon the railway-tracks of said system; contact-rails in the electric circuit connected through suitable 60 conductors with said switch mechanism and one pole of an electric battery; electric conductors communicating between said electric signal in the locomotive including the axle, and wheels of the locomotive, the track and 65 wire or ground circuits with the other pole of the battery and an electric conductor communicating with said signal, which conductor is adapted to be brought in connection with said contact-rails as the locomotive is 70 passing the same, whereby the electric circuit between the battery and said signal will be closed and the signal in the locomotive actuated as the same is passing said contact-rails, substantially as specified.

4. In a railway signal system, the means herein described for simultaneously setting the air-brakes and actuating the signal in a locomotive comprising a winding-drum, a drum-actuating weight; a flexible connection 80 for suspending such weight from the drum; an electromagnet; an armature slidably supported in close proximity to said electromagnet; a drum-retaining pawl connected with said armature; an air-controlling valve; 85 means for actuating said valve from said weight-actuated drum; an electric generator; electric conductors communicating between said generator and said electromagnet and means for automatically closing the electric 90 circuit between said generator and electromagnet, whereby the same electric current which is used to actuate the signal in the locomotive at a distance may also cause the air-brakes to be simultaneously actuated, 95 substantially as, and for the purpose specified.

In testimony whereof I affix my signature in the presence of two witnesses.

JOHN NEUMAIER.
